[57] CLAIM

An ornamental design for a transcutaneous nerve stimulator case, as shown and described.

DESCRIPTION

FIG. 1 is a front elevation of a transcutaneous nerve stimulator case showing my new design;
 FIG. 2 is a rear elevation thereof;
 FIG. 3 is a top plan view thereof;
 FIG. 4 is a bottom plan view thereof;
 FIG. 5 is a right side elevation thereof; and
 FIG. 6 is a left side elevation thereof.

FIG. 1.

FIG. 5.

FIG. 3.

FIG. 2.

FIG. 6.

FIG. 4.
